UNITED STATES PATENT OFFICE.

LOUIS GODDU, OF BRAINTREE, MASSACHUSETTS.

FEATHER-EDGING MACHINE.

Specification forming part of Letters Patent No. 44,300, dated September 20, 1864.

To all whom it may concern:

Be it known that I, LOUIS GODDU, of Braintree, Norfolk county, Massachusetts, now temporarily residing at Montreal, Canada, a subject of the Queen of Great Britain, having made oath of intention to become a citizen of the United States, have invented Improvements in Feather-Edging Machines; and I do hereby declare that the following, taken in connection with the drawings which accompany and form part of this specification, is a description of my invention sufficient to enable those skilled in the art to practice it.

My improvement relates principally to the construction of machines for feather-edging or chamfering and reducing to an even thickness soles for boots and shoes, the invention consisting, chiefly, in the employment, in connection with feed-rolls and a surface against which the edge of the sole is guided, of a pointed instrument, or directing rod or bar, which keeps the edge of the sole up to the guiding-surface; also, in the employment, in connection with the feed-wheels, of "dinking-points" upon the lower feed-wheel, for the purpose of dinking or spacing the peg-holes in the bottom of a sole; also, in so arranging the chamfering-knife, the rolls, and the directing-rod that while the knife keeps a fixed relation to the lower feed-roll and the plate upon which the sole rests the guide-rod and upper roll yield to the inequalities of thickness of the sole; also, in so constructing the machine that the knife and upper roll are raised and lowered and fixed in position together, to adapt the machine to stock of varying thickness; also, in giving the surface upon which the sole rests and the bearing-surface of the feed-rolls an inclination with respect to the horizontally-arranged cutting-edge of the skiving-knife.

In the drawings, Figure 1 represents a side elevation of a machine embodying my invention. Fig. 2 is a front view, and Fig. 3 a side elevation, of the head of the machine, these views being full size, while Fig. 1 is one-half size of the machine.

a denotes the frame; *b*, a horizontal driving-shaft, carrying on its front end the lower feed-wheel, *c*. This shaft has a gear, *d*, which meshes into a similar gear, *e*, on another shaft, *f*, which carries the upper feed roll, *g*. The lower shaft rotates in stationary bearings, while the upper shaft is journaled in movable

boxes, the front one, *h*, of which is capable of vertical movement in the head *i*. A spring, *k*, presses the journal with the upper feed-roll in a downward direction, the pressure being regulated by a screw, *k'*. The skiving or feather-edging knife is seen at *l*. The cutting-edge of the knife is horizontal, while the surface of the feed-roll and the plate *y*, upon which the sole rests, are inclined, to conform to the inclination to be cut upon the surface of the sole, and as they pinch the edge between them they bear it in an inclined position against the knife-edge, causing the upper edge to be chamfered or skived off, as will be readily understood. Now, in other machines of this character where feed rolls are used and a knife is to operate on or parallel to the edge, it is necessary to hold or guide the edge by hand up to the surface against which it is to bear to regulate the cut. I dispense with this necessity by applying the guiding or directing rod *m*. This rod extends down through two projections, *n*, from the head *i*. Its lower end is inclined, as seen in the drawings, down to a rounding point. This point extends a little below the plane of the lower edge of the top roll, so that it shall impinge against the upper surface of the sole, the sole being pinched between this point and the surface of the plate *y* beneath as well as between the adjacent surface of the two feed-rolls. A collar-plate, *p*, is fastened to the rod just above the lower projection *n*, and a spring, *q*, bearing against this collar and the upper projection *n*, keeps the guide-rod down. To raise it to insert a sole, a lifter-lever, *r*, is jointed to the top of the bar, and the collar-plate is so applied that it can be raised or lowered and fastened in position to adjust the distance of the point of the rod *m* to the thickness of the sole being operated upon.

The operation of the machine is as follows: The sole being inserted and the point of the rod *m* let down thereupon, the edge of the sole being against the front side of the head *i*, as the feed-wheels turn the point *s* has a tendency to stop the sole, but the points on the feed-wheels carry it on, and these teeth being between the points *s* and the guide-face *t*, they swing the sole *m*, and as the sole is fed the teeth on the feed-wheels keep up their pressure on the sole inside of the point *s*, and keep the edge of the sole against the surface *t*;

hence the sole cannot be fed out, but will continue to be fed round its edge so long as the feed-wheels are turned.

To remove the sole when skived, the pointer-rod is lifted, when the teeth will feed the sole in a straight line until it is run out of the machine.

The spring *q* and the spring *k* allow the guiding-point *s* and the upper feed-roll to yield to the inequalities of the stock; but while the machine is in operation the knife cannot move, so that, however unequal in thickness the stock is, the edge of the sole is trimmed to a uniform thickness.

To adapt the machine to stock of different thicknesses, and regulate the thickness given to the edge of the sole correspondingly, the knife and upper roll are so applied as to be movable together for the purpose of adjustment. The knife is fixed between plates *x*, the lower one of which is fixed upon the top of an adjusting-screw, *u*. A projection, *v*, extends from this plate under the journal-box *h*, so that when the knife is raised by the screw *u* the box *h* and the upper feed-wheel are raised with it, and when the knife is lowered by the screw the spring *k* keeps the box in contact with the projection *v*, thus maintaining the knife and feed-roll in the same relative normal position, while the projection does not prevent the roll from rising independently of the knife for the varying thickness of the sole.

In pegging soles by hand it is customary to space off holes for the insertion of the awl and peg; but such spacing is imperfectly effected by hand. To adapt this machine to such purpose, the teeth *o* on the lower roll are arranged at the distance from the bearing-surface *t* that the pegs are usually driven from the edge of the sole. As the sole is fed, these teeth or points puncture holes parallel to or equidistant from the edge of the sole, which holes answer for the insertion of the points of the pegs. The lower roll may be made capable of falling, to allow the introduction of the sole between the rolls, and one or both rolls may be removable for replacement by others.

of varying inclination, to alter the inclination of the chamfering cut. A friction-roll may also be used, instead of the stationary surface-plate.

I will here remark that though I have described the adaptation of the guiding-rod *m* to a machine for feather-edging soles, it may be applied to other machines in which stock is to be trimmed or operated upon in a line or lines equidistant from the edge of such stock or from the edge of a pattern or plate upon which such stock may be fixed—as, for instance, channeling or grooving knives may be employed instead of or in connection with the skiving-knife; or an upright knife may be fixed to the head *i*, or otherwise so arranged as to cut or form the shape of the sole from a pattern, which pattern is held against the guiding surface *t* by the rod *m*. These and various other modifications may be embodied upon the machine without departing from the spirit of that part of my invention relating to the employment of the guiding-rod *m*.

I claim—

1. In connection with feeding and cutting mechanism and a guiding surface, the employment of a directing rod or point to keep the stock against the guiding-surface.
2. The construction of the lower feed-roll with dinking-points so arranged as to puncture and space the holes for the peg-points, substantially as described.
3. The arrangement of the mechanism by which, while the knife in operating has a fixed relation to the surface of the lower feed-roll, the directing-rod and upper feed-roll yield to the inequalities of the stock.
4. The construction by which the knife and upper feed-roll are raised, lowered, and fixed in position together, substantially as set forth.
5. Combining a horizontal skiving-knife with inclined-surface feed-rolls, in the manner and for the purpose substantially as set forth.

LOUIS GODDU.
